APPARATUS FOR HANDLING GASES

Harry Hooper, Somerville, N. J., assignor to Air Reduction Company, Incorporated, New York, N. Y., a corporation of New York

Application March 9, 1948, Serial No. 13,863

1 Claim. (Cl. 62—1)

1

This invention relates to apparatus for heating gases, being adapted especially to the delivery of carbon dioxide gas from a higher to a lower pressure, although it may be used in dispensing gases other than carbon dioxide. In the dispensing of carbon dioxide, pressure-reducing valves are employed in order to effect the necessary reduction of the pressure of the gas from that of the container in which it is shipped to the pressure at which it is to be used. The cooling of the gas, due to expansion, often causes the formation of solid carbon dioxide and the freezing of precipitated moisture, which collects in the pressure-reducing valve and at the valve seat. Solid carbon dioxide and ice in the valve interfere with its operation and sometimes completely stop the gas flow. This difficulty can be obviated by warming the high pressure gas before it reaches the pressure-reducing valve. If there is a constant demand no difficulty is experienced because the heat input can be regulated readily so as to impart sufficient heat to the gas to prevent freezing without raising the temperature of the gas to a point where it is likely to damage the internal parts of the pressure-reducing valve.

When the gas flow is not constant, or the flow is at a low rate or is completely stopped for periods, the simple expedient mentioned is not satisfactory because the gas is certain to become overheated at intervals with resulting damage to the pressure-reducing valve. Moreover, overheating of the gas is undesirable because of its inefficiency. In many applications, the low pressure carbon dioxide is dissolved in water, and the solubility of carbon dioxide in water varies inversely with the temperature. Thus, if the gas is heated materially above the minimum required to prevent the formation of solid carbon dioxide or ice, energy is wasted in heating the gas and again in cooling the water in which the gas is dissolved. It has been proposed heretofore to heat carbon dioxide, prior to expansion, by passing it through coils submerged in a heated liquid bath. The amount of heat supplied to the bath is controlled by the rate of gas flow. While the system is satisfactory under some conditions, it is not sufficiently flexible to follow very wide or rapidly changing flow conditions. Since the heat is supplied indirectly to the gas through the liquid bath, there is an inherent time delay in its response.

An object of this invention is to provide a gas heating system of the demand type that will efficiently maintain a constant gas delivery temperature.

Another object is to provide a gas heater which reacts quickly to changes in rates of gas delivery and minimizes residual heating effects.

A further object is to provide a unit of the

2

type described which is neat and compact in structure and will function equally well when mounted in any position.

Another object is to provide a demand-type heater which responds to actual gas delivery temperature variations rather than flow variations, and which automatically compensates for extraneous temperature variations such as the temperature of the high pressure gas and the variations in atmospheric temperature surrounding the installation.

Another object is to provide an efficient demand-type heater in which the energy is introduced directly into the gas stream with very little heat loss to surrounding parts.

Other objects and advantages of the invention will be apparent as it is better understood by reference to the following specification and accompanying drawing, in which

20 Fig. 1 is a plan view of an apparatus embodying the invention assembled with a pressure-reducing valve of conventional design;

Fig. 2 is a view in elevation partly in section of the heater and pressure-reducing valve as shown in Fig. 1;

Fig. 3 is an enlarged sectional view of the heater on the line 3—3 of Fig. 1; and

Fig. 4 is a diagram showing the electrical circuit employed.

30 Referring to the drawing, 5 indicates a pressure-reducing valve commonly called a "regulator," in which the pressure of the entering gas is reduced to the desired point. The pressure reducing valve is of conventional design and need not be described in detail. Any of the commonly used types of pressure reducing valve may be employed in the apparatus. As is usual in such equipment, a pressure gauge 6 indicates the inlet pressure, and a pressure gauge 7 indicates the outlet pressure. The valve 5 is adjustable to permit the desired reduction of the pressure of gas flowing therethrough.

45 Supported on and connected to the pressure-reducing valve is a casing 8 enclosing a heating chamber or passage 14 which has an inlet connection 9 for the gas at high pressure. The details of construction of the heater and of the regulator therefor will be described hereinafter.

50 The gas, after entering the heating chamber, passes therethrough and escapes through a passage 10 to a pipe 11 which conveys it to the inlet connection 12 of the pressure-reducing valve 5. The gas at low pressure escaping from the pressure-reducing valve 5 is withdrawn through a flexible connection 13 and delivered to a regulator chamber or passage 25 which controls the heating effect in the heating chamber. Thence it escapes through an outlet connection 15 and is delivered to the point where the gas is utilized.

55

Thus, all of the gas entering through the inlet 9 is subjected to heating to the required temperature. It expands in the pressure-reducing valve, the cooling effect of expansion being compensated by the heat introduced to the gas. The temperature of the gas entering the chamber 25 regulates the temperature of the gas entering the chamber 14. Hence, regardless of variations in rates of flow there is always precisely the amount of heat input to balance the cooling effect of expansion, and there is no possibility of cooling the pressure-reducing valve to the point where solid carbon dioxide or ice may be formed therein. At the same time, overheating of the gas is avoided. If the outlet temperature of the gas drops, more heat is immediately supplied to the heating chamber. On the other hand, if the temperature of the outlet gas rises, heat is cut off in the heating chamber and the desired temperatures in the inlet and outlet gases are maintained substantially constant.

Referring to Figs. 3 and 4, within the heating chamber 14 is a core 16 of ceramic or other suitable insulating material which supports a heating element 17 of high resistance conducting material such as is commonly used in electrical heaters, for example Nichrome wire. Of course, platinum or any other metal having necessary resistance could be employed as the heating element. One lead 18 extends through a bore in the core 16, and the heating element 17 is disposed helically about the core, terminating in a lead 19. Conductors 20 and 21 extend through an insulating cap 22 which is secured in gas-tight relation at one end of the chamber 8 by a cap 23. The other end of the chamber is closed by a plug 24. There is sufficient space around the core 16 to permit the flow of gas from the inlet 9 longitudinally of the casing to the point where it escapes through the passage 10.

Formed preferably in the same casing 8 is a regulator chamber 25, closed at one end by a plug 26 and at the other by a threaded nut 27. Within the chamber 25, a metallic sleeve 28 is supported by the nut 27. The lower end is closed by a wall 29. Mounted within the sleeve and supported at one end by a stud 30 and at the other by a stud 31 are flexed members 32 and 33, carrying contact members 34 and 35. The contact member 34 is connected to the conductor 21, and the contact member 35 is connected to a conductor 36. The conductors 20 and 36 terminate in a plug 37 which is connected to a source of current through a conductor 38. Thus the contacts 34 and 35 are in series in the electrical circuit, as shown more clearly in the diagram Fig. 4. When the temperature of the gas flowing about the sleeve 28 rises, the sleeve expands and the members 32 and 33 straighten until contact is broken between the contacts 34 and 35. This shuts off the supply of current to the heating element 17. When the temperature of the gas falls, the sleeve 28 shrinks and the contacts 34 and 35 are again brought together, closing the circuit and thus supplying current to the heating element 17. Consequently, any variation in the temperature of the outlet gas results promptly in modification of the amount of heat supplied to the incoming gas, and the temperature of

the outlet gas is thus maintained at a substantially uniform point and the temperature of the inlet gas is held to the point which compensates for the reduction of temperature due to expansion when permitting cooling to the point where solid carbon dioxide or ice could form in the pressure-reducing valve.

While I have illustrated and described a particular form of thermostat adapted to regulate the amount of current supplied to the heating element 17, it is to be understood that any other effective form of thermostat may be substituted therefor. It is necessary merely that the thermostat be sufficiently sensitive to variations of temperature in the outlet gas to ensure that the inlet gas is heated to the required temperature. Regardless of the rate of flow or intermittent stoppages of the flow of the gas, the inlet gas will be heated sufficiently to accomplish the purpose of the invention.

Various changes may be made in the details of the construction and arrangement of the parts without departing from the invention or sacrificing the advantages thereof.

I claim:

An apparatus for delivering gases from a higher to a lower pressure including a pressure-reducing valve, a casing having a plurality of longitudinal extending gas passages therein, an electrical resistance heater positioned in one of said passages for direct contact with gas flowing therethrough, thermostatic means positioned within a second of said passages responsive to the temperature of gas flowing therethrough to regulate the heating effect of said heater, means for introducing gas into one end of the passage containing the heater and means for discharging gas at the other end, whereby gas is caused to flow through said passage over and in contact with said heater, a passageway communicating at one end with the discharge end of the passage containing the heater, means for attaching said casing to said valve at the discharge end of said passageway, said attaching means having a passage therethrough for delivering gas from said passageway to the inlet side of said valve and a flexible conduit between the valve and the passage containing the thermostatic means for delivering gas from the discharge side of said valve into contact with the thermostatic means, whereby the temperature of gas delivered to said valve is maintained within predetermined limits.
